UNITED STATES PATENT OFFICE.

MYRON S. FELTON, OF FOLSOM, CALIFORNIA.

EXTENSIBLE SUPPORT.

1,171,974.

Specification of Letters Patent. Patented Feb. 15, 1916.

Application filed January 13, 1915. Serial No. 1,978.

To all whom it may concern:

Be it known that I, MYRON S. FELTON, a citizen of the United States, residing at Folsom, in the county of Sacramento and State of California, have invented new and useful Improvements in Extensible Supports, of which the following is a specification.

This invention relates to an extensible support.

The object of the present invention is to provide an extensible support for drawers, shelves, and the like, in the form of a lazy tong structure, which is simple and substantial in construction and from which the drawers or shelves may be easily and quickly removed for cleaning, renewal or other purposes.

Further objects of the invention will hereinafter appear.

The invention consists of the parts and the construction and combination of parts as hereinafter more fully described and claimed, having reference to the accompanying drawings, in which—

Figure 1 is a vertical longitudinal section on line 1—1, Fig. 2. Fig. 2 is a vertical transverse section on line 2—2, Fig. 1. Fig. 3 is a detail perspective view of the connection formed between the lazy tong frames and the drawer supporting bar. Fig. 4 is a similar view showing the relative position of the two track bars.

A indicates a suitable support, such as a filing case, shelf, frame, or the like. Secured on each side 2 of said case or frame in a horizontal plane and directly opposite to each other is a pair of angle iron track bars 3 and 4, and extending between said bars and journaled in their rear ends is a shaft 5 to which is attached the inner links of a pair of lazy tong frames 6 and 7, there being one frame adjacent to each side section 2. The inner lower link 8 of each lazy tong frame is secured to shaft 5, while the upper links 9 are turnable thereon. The mounting of the lazy tong frames in this manner causes the frames to move out in unison when they are extended and will thus prevent any side rocking or binding action with relation to the sides of the shelf or drawer carried between the lazy tong frames.

The lazy tongs are, as previously stated, adapted to support a drawer, shelf or any other suitable article. In the present in-

stance a drawer B has been illustrated and this is mounted or supported between the lazy tong frames in the following manner: Secured on the central pivots 10 and 11 of the lazy tongs, both inside and outside, are rollers 12 and 13 respectively, and secured to each side of the drawer is a pair of angle iron track bars 14 and 15 which are adapted to rest on the rollers 13. The angle bars 14 and 15 are reversed in position with relation to the bars 3 and 4 and will, therefore, rest on rollers 13, while angle bars 3 and 4 will serve as supports or tracks for the rollers 12.

The outer ends of the angle bars 14 and 15 are provided with pockets 16 for the reception of the outer rollers 17. In this manner a connection is formed between the lazy tong frames and drawer by which the two will move in unison when pulled in or out with relation to the main supporting frame A.

In operation, it is only necessary to extend the lazy tong frames to the position indicated at 18. The drawer is then placed between said frames in a position where the track bars 14 and 15 will rest upon the rollers 13 and where the pockets 16 will engage the outer rollers to form the connection previously described. The drawer with connected frames may now be moved back into the main supporting frame A, causing the lazy tongs to fold up, as indicated at C. The connection formed between the lazy tong frames by means of shaft 5 causes these to move in unison, thereby preventing any binding action at any point. The provision of rollers 12 and 13 furthermore prevents binding action and permits the drawer to be easily pulled out by means of a handle 19. The construction involved also permits the drawer, shelf, or other device, supported by the lazy tongs to be quickly removed or replaced at any time, making the device applicable for many purposes.

The materials and finish of the several parts of the extensible support are such as the experience and judgment of the manufacturer may dictate.

I wish it understood that various changes in form, proportions and minor details of construction may be resorted to within the scope of the appended claims and that I do not wish to limit myself to the specific design and construction here shown.

Having thus described my invention, what

I claim and desire to secure by Letters Patent is—

1. An extensible frame comprising a main supporting frame, a pair of spaced lazy tong frames supported at their inner ends on the main frame, inner and outer rollers mounted centrally on each lazy tong frame, L-shaped tracks mounted on the main frame for supporting the outer rollers of the lazy tong frames, a drawer disposed between the latter, and an inverted L-shaped track on each side of the drawer to engage with and be supported by the inner rollers.

2. An extensible frame comprising a main supporting frame, a pair of spaced lazy tong frames supported at their inner ends on the main frame, inner rollers mounted on the central and outer end portions of each lazy tong frame, a drawer arranged between the lazy tong frames, and an angle iron track secured to each side of the drawer and slidably supported by the central roller of the respective lazy tong frame, the outer end of each track being formed with a downwardly opening pocket for receiving the outer end roller of the adjacent lazy tong frame.

3. An extensible frame comprising a main supporting frame, a shaft journaled in said frame, a pair of interspaced lazy tong frames supported at their inner ends on said shaft, one of the inner links of each lazy tong frame being secured to the shaft and the other link being turnable thereon, inner and outer rollers mounted on the central pivots of the lazy tong frames, a track bar on each side of the main supporting frame upon which the outer rollers are guided and supported, and a drawer mounted between the lazy tong frames and supported on the inner rollers.

4. An extensible frame comprising a main supporting frame, a shaft journaled in said frame, a pair of interspaced lazy tong frames supported at their inner ends on said shaft, one of the inner links of each lazy tong frame being secured to the shaft and the other link being turnable thereon, inner and outer rollers mounted on the central pivots

of the lazy tong frames, a track bar on each side of the main supporting frame upon which the outer rollers are guided and supported, a drawer mounted between the lazy tong frames and supported on the inner rollers, and a connection formed between the drawer and the lazy tong frames.

5. An extensible frame comprising a main supporting frame, a shaft journaled in said frame, a pair of interspaced lazy tong frames supported at their inner ends on said shaft, one of the inner links of each lazy tong frame being secured to the shaft and the other link being turnable thereon, inner and outer rollers mounted on the central pivots of the lazy tong frames, a track bar on each side of the main supporting frame upon which the outer rollers are guided and supported, a drawer, a track bar secured on each side of said drawer, said track bars being guided by and supported on the inner rollers, and a connection formed between said track bars and lazy tong frames.

6. An extensible frame comprising a main supporting frame, a shaft journaled in said frame, a pair of interspaced lazy tong frames supported at their inner ends on said shaft, one of the inner links of each lazy tong frame being secured to the shaft and the other link being turnable thereon, inner and outer rollers mounted on the central pivots of the lazy tong frames, a track bar on each side of the main supporting frame upon which the outer rollers are guided and supported, a drawer, a track bar secured on each side of said drawer, said track bars being guided by and supported on the inner rollers, and a pocket formed in the outer end of each of said track bars into which the outermost of the inner rollers is adapted to extend.

In testimony whereof I have hereunto set my hand in the presence of two subscribing witnesses.

MYRON S. PELTON
